UNITED STATES PATENT OFFICE.

MILLER REESE HUTCHISON, OF NEW YORK, N. Y., ASSIGNOR, BY MESNE ASSIGNMENTS, TO AKOUPHONE MANUFACTURING COMPANY, A CORPORATION OF NEW YORK.

APPARATUS FOR CHARGING BATTERIES.

SPECIFICATION forming part of Letters Patent No. 691,144, dated January 14, 1902.

Application filed July 19, 1901. Serial No. 68,918. (No model.)

To all whom it may concern:

Be it known that I, MILLER REESE HUTCHISON, a citizen of the United States, residing at the city of New York, in the borough of 5 Manhattan and State of New York, have invented certain new and useful Improvements in Apparatus for Charging Batteries, of which the following is a full, clear, and exact description.

10 This invention relates to apparatus for aiding in the charging of secondary batteries, which I have specifically termed a "charging-cord." It is intended to be interposed between the battery and a source of electricity, 15 such as a wall-socket or other fixture. The device is to be used in connection with certain telephonic apparatus used by deaf persons as an aid to hearing, such apparatus being electrical and provided at various points 20 with a specific type of electrical connector, so that all of the parts can be interconnected quickly. It is necessary that the said charging-cord of the present invention should be equipped with the same kind of connectors 25 to be applicable to the general system of apparatus. This connector in general consists of a block of such shape as to be conveniently grasped in the fingers and provided with a metallic pin and a metallic socket constituting 30 male and female electric terminals. This device is to be used in conjunction with another of the same character, the two together constituting the complete connector and adapted to be connected by inserting the 35 male terminal of one block into the female terminal of the other block.

The storage battery, which constitutes a part of the said apparatus used by deaf persons, is fitted with one of these blocks having 40 the male and female terminals, so that it can be readily connected with the charging and discharging circuits. In charging a storage battery it is necessary to connect the charging-circuit therewith in such a way as 45 to send the current through the battery in the proper direction for charging, and such batteries being commonly charged from an incandescent lamp or from a wall-receptacle there is ordinarily no means of ascertaining 50 the polarity of the current taken from such

sockets or fixtures. Now it is obvious that if a simple charging-cord were used which carried the ordinary plug for connection with the fixture at one end and a single block with the male and female terminals described at 55 the other end the battery could only be charged when the current was flowing in one direction, for it is obvious that the male and female terminals could only be adjusted to the corresponding battery-terminals in one 60 way, a reversal not being possible. I therefore provide a charging-cord having at one end an ordinary plug for connection with the current-outlet and at the other end having two of the said blocks, each carrying male 65 and female terminals, with the male terminal of one block and the female terminal of the other connected to one side of the circuit, while the other two terminals are connected to the other side of the circuit. Thus after 70 first ascertaining the polarity of the current the proper terminal can be adjusted to the battery and the charging accomplished. In order to ascertain the polarity of the current, I use an ordinary simple form of polarity-indicator, which will hereinafter be referred to. 75

In the accompanying drawings, Figure 1 is an illustration of my improved charging-cord. Fig. 2 is a view of an ordinary form of polarity-indicator, and Fig. 3 indicates conventionally the storage battery and its predetermined 80 form of connector.

As before described, the connector used throughout my system of apparatus consists of a block, (indicated in the several figures by 85 the letter *a*.) This block is of insulating material and carries a female metallic sleeve or socket *a'* and a metal pin *a*², constituting male and female parts. These connecting devices are all duplicates of each other, and it will 90 be seen that any two of them can be connected together to constitute a double pole-connector. The storage battery *A* is provided with one of these connectors, which in practice is mechanically fastened to some portion 95 of the containing vessel, but which is here shown separate and merely connected with the battery by circuit-wires 1 and 2.

B is an ordinary form of polarity-indicator, consisting of a short glass tube *b*, containing 100

a liquid adapted to be discolored by the passage of current and having a pair of electric terminals located at the ends, between which the current is to be directed through the liquid. This indicator is also connected with one of my connectors *a*, having usual male and female terminals.

The device constituting the particular feature of my invention consists of the charging-cord *C*. This is provided at one end with an ordinary plug *c* for connection with a current-outlet. As shown, this plug is provided with an external screw-thread *c'* and a center contact *c''*, adapted to engage with corresponding terminals at the outlet; but any other form of plug to correspond with the terminals at the outlet may be used. From each of these contacts a flexible insulated conductor *e* and *e'*, respectively, leads. These conductors will ordinarily be twisted together and of suitable lengths. At the other end both of said conductors branch into two parts, the branches of conductor *e* being indicated by *f* and *g*, and the branches of *e'* being indicated by *g* and *f'*. To the outer end of the cord are attached two of the connectors *a*, the female terminal of one being connected to the branch *f* and the male terminal to the branch *f'*, while the female terminal of the other is connected with the branch *g* and the mate with *g'*. Thus in each of the blocks *a* one of the terminals is positive, while the other is negative; but in one case the positive terminal is the male, while in the other it is the female.

As it is essential in charging some batteries from circuits carrying the usual high commercial voltages to introduce a resistance in series with the battery, I connect with one conductor of my charging-coil an ordinary incandescent-lamp socket *I*, into which a lamp may be adjusted during the charging operation; but this is not an essential feature of my invention, inasmuch as the same results can be obtained by the use of tap-sockets or other appliances.

It will be seen that when one of the connectors attached to the cord *C* is adjusted to the battery-connector, while the plug *c* is inserted in the current-outlet, a current of a certain polarity will be sent through the battery, while if the other connector attached to the cord is inserted in the battery-connector a current of the opposite polarity will flow through the battery from the same current-outlet. Hence as there is no way ordinarily provided to ascertain the polarity of the current at the current-outlet I utilize the polarity-indicator *B*. I first insert one of the connectors attached to cord *C* into the connector on the indicator. If the result is to turn the liquid red adjacent to a certain one of the electrodes in the tube, then that indicator is the proper one to use on the battery, and it can be inserted in the battery-connector at once and the charging accomplished; but if the particular connector used happens to turn

the liquid red around the other electrode in the tube it will be known at once that that connector should not be used in charging the battery. If the insertion at one of the connectors on the cord *C* turns both ends of the tube red, it is an indication that the current is alternating and should not be used at all for charging. It will therefore be seen that with a charging device of this character an unskilled person who finds it necessary to use the apparatus I have hereinbefore referred to will have no difficulty in charging the battery himself, it being necessary only to educate him in the use of the polarity-indicator.

Obviously the branches *f f'* and *g g'* may commence directly at the plug *c*; but for economical reasons it is better to branch the main cord near the outer end, where the connectors are attached.

Having described my invention, I claim—

1. An electrical device consisting of a pair of conductors adapted to form the positive and negative sides of a circuit, in combination with two connectors each having a positive and a negative terminal respectively connected with said two conductors.

2. An electrical device consisting of a pair of conductors adapted to form the positive and negative sides of a circuit, in combination with two connectors each having male and female terminals connected respectively with the two conductors.

3. An electrical device consisting of a pair of conductors adapted to form the positive and negative sides of a circuit, and mechanically connected to form a flexible cord, said cord having at one end a device for connection to a source of electricity and at the other end, two connectors each having two terminals in character differing from each other but being the same on each connector and a different terminal of the other connector being connected with one of said conductors while the other two terminals are connected with the other conductor, substantially as described.

4. An electrical device consisting of a pair of conductors adapted to form the positive and negative sides of a circuit, in combination with two connectors each having a male and a female terminal, the male terminal of one and the female terminal of the other being connected to one of said conductors, and the other two terminals being connected to the other conductor, substantially as described.

5. The combination of two mechanically-joined connectors of like character, each having two terminals of different form, and means for connecting them with a current outlet or source, for the purpose set forth.

6. An article of manufacture, consisting of a flexible cord composed of two conductors, a circuit-connecting plug at one end, two connectors each having two terminals at the

other end and a lamp-socket connected in series in one of the conductors, substantially as described.

7. The combination of a battery having a connector provided with two terminals of differing character, a polarity-indicator having a similar connector and a charging-cord for the battery consisting of two conductors and two connectors each similar to the other connectors and adapted to fit the same, the terminal of one connector and a different ter-

2
minal of the other connector being attached to one of said conductors while the other two terminals are connected with the other conductor.

15
In witness whereof I subscribe my signature in presence of two witnesses.

MILLER REESE HUTCHISON.
